UNITED STATES PATENT OFFICE.

THEODORE BUMANN, OF LITCHFIELD, ILLINOIS.

SAFETY DEVICE FOR POWER-PRESSES.

1,091,117.

Specification of Letters Patent. Patented Mar. 24, 1914.

Application filed June 5, 1913. Serial No. 771,986.

To all whom it may concern:

Be it known that I, THEODORE BUMANN, a citizen of the United States, residing at Litchfield, in the county of Montgomery 5 and State of Illinois, have invented certain new and useful Improvements in Safety Devices for Power-Presses; and I do declare the following to be a full, clear, and exact description of the invention, such as will enable others skilled in the art to which it 10 appertains to make and use the same.

This invention relates to safety devices for manually controlled power driven presses and other machines.

15 The object of the invention is to provide a simply constructed and efficient device which may be readily applied to any machine already constructed and which will render it necessary for the operator to use 20 both of his hands at points remote from the plunger or other power operated part of the machine to start the machine thus positively preventing injury to the hands of the operator.

25 Another object is to provide a device of this character which can be manufactured and applied to machines at small expense and which will not materially increase the labor of operating the machine or prevent 30 the rapid operation thereof.

This invention consists primarily in a safety appliance for hand fed power presses embodying therein a locking device for the 35 treadle which operates the tripping mechanism of the machine and means for preventing said locking device from being released until both hands of the operator are moved away from the dies.

With these and other objects in view, the 40 invention consists of certain novel features of construction, and the combination and arrangement of parts as will be more fully described and claimed.

In the accompanying drawings: Figure 1 45 represents a perspective view of a power press equipped with this improved safety appliance, said appliance being shown in inoperative position; Fig. 2 is a front elevation of a portion of a press equipped with 50 this improved safety device and with the parts in the same position as shown in Fig. 1; Fig. 3 is a side elevation thereof with the device in operative position; Fig. 4 is a detail perspective view of the treadle locking 55 lever.

In the embodiment illustrated one form

of stamping press A is shown of which there are numerous types but it is to be clearly understood that this improved safety device is equally applicable to all. In the 60 parts here shown a indicates the frame which carries the bed for the die indicated at b, the plunger is indicated at c, a fly wheel d and a trip actuating treadle e, all of which parts are old and well known and consequently a detail description and illustration thereof are not deemed necessary.

This improved safety device comprises a lever 1 shown in detail in Fig. 4, as hinged at its lower end to the floor within the base 70 of the machine adjacent the treadle e and has a notch or step 2 formed near said lower end in position to engage the treadle e when in raised position and hold it against downward movement. A coiled spring 3 connects 75 this lever with the frame a and exerts its tension to draw said lever toward the treadle e to cause the step 2 thereof to normally engage said treadle and hold it against actuation. The upper end of this lever 1 has an 80 operating handle 4 here shown in the form of a laterally extending bent terminal projecting outward for convenience of the operator and this lever is slidably mounted on the frame a and is guided in its movements 85 and held by a strap 5 secured to the frame a at the front of the machine and spaced a suitable distance therefrom to permit the lever to move readily between it and the frame as shown clearly in Fig. 1. When 90 this lever 1 is moved to its limit toward the left the step 2 thereof will be moved from under the treadle e and said treadle will be then ready for actuation or depression by the foot of the operator, the lever being held 95 in this position by the hand of the operator, against the tension of the spring 3 and when released the said spring will move it automatically toward the right of the machine into locking position for holding the treadle 100 in raised position.

A guard plate 6 is hingedly mounted at the front of the frame on the bed supporting the die b and is adapted to be raised and lowered for a purpose now to be described. 105 This guard when lowered extends laterally from the bed of the machine in substantially the same plane therewith and it cannot be so lowered until the lever 1 is moved to its extreme limit toward the right as the 110 lever projects above the bed of the machine and prevents the lowering of said plate

or guard until moved to its extreme limit toward the right. When said lever is in this position the plate may be lowered as shown in Fig. 3 and it will lock said lever 5 against movement toward the left and thereby hold it securely in engagement with the treadle *e*, and thus prevent actuation of the treadle.

When it is desired to depress the treadle 10 for actuating the plunger *c* the guard 6 must first be raised and the lever 1 moved toward the left to disengage the step 2 thereof from the treadle *e* and to accomplish this it is necessary that both hands 15 of the operator be used, one to raise the plate 6 and the other to move the lever 1 to the left thus insuring that both hands will be out of the way of the plunger before the treadle *e* is depressed for throwing the 20 plunger into operation. When raised this plate 6 also forms a guard extending between the operator and the dies of the machine and thus preventing accidental insertion of the operator's hands between the dies 25 and consequent injury thereto.

While I have described my invention with more or less minuteness as regards details and as being embodied in certain precise forms, I do not desire to be limited 30 thereto unduly any more than is pointed out in the claims. On the contrary, I contemplate all proper changes in form, construction and arrangement, the omission of immaterial elements and substitution of 35 equivalents as circumstances may suggest or render expedient.

I claim as my invention:

1. The combination with a power press having a tripping treadle; of an upright 40 swinging lever having means for engaging the treadle to support it in raised position, resilient means for holding said lever normally in engagement with said treadle, and a pivotally mounted member swinging in a

plane at right angles to that in which the 45 lever swings for locking said lever in engagement with said treadle when the treadle is in inoperative position.

2. The combination with a power press having a tripping treadle, of a lever having 50 means for engaging the treadle to support it in raised position, resilient means for holding said lever normally in engagement with said treadle, and pivotally mounted means for locking said lever in engagement 55 with said treadle when the treadle is in inoperative position.

3. The combination with a power press having a tripping treadle, of a lever fulcrumed adjacent said treadle and having 60 means for supporting it normally in raised inoperative position, a hinged guard plate adapted to be lowered when said lever is in locking engagement with said treadle for holding the lever in this position, said lever 65 projecting in position to prevent the lowering of said plate when the lever is out of engagement with said treadle.

4. The combination with a power machine having a tripping treadle, a lever fulcrumed adjacent said treadle and having 70 means for normally holding the treadle in raised inoperative position, guide means for said lever mounted on said machine and having stops for limiting its movement in 75 opposite directions, and a hinged plate mounted to be lowered when said lever is at its extreme limit in one direction whereby said lever is locked in this position, said plate being held against lowering when the 80 lever is moved in the opposite direction.

In testimony whereof I have hereunto set my hand in presence of two subscribing witnesses.

THEODORE BUMANN.
